UNITED STATES PATENT OFFICE.

WILLIAM R. GILLIES, OF CHICAGO, ILLINOIS, ASSIGNOR TO EQUIPMENT SPECIALTIES CO., OF CHICAGO, ILLINOIS, A CORPORATION OF ILLINOIS.

MEANS FOR SEALING WALL AND FLOOR JOINTS, ETC.

Application filed September 12, 1924. Serial No. 737,233.

My invention is concerned with the provision of improved means for sealing the joints between walls and floors, etc., and is particularly concerned with the provision 5 of means for sealing the joints between the floors and inside walls of railway refrigerator cars.

Nowadays in shipping certain classes of perishable produce it has become customary 10 to place ice in the main compartment of the car, that is, between the bulk heads, with the result that water collects upon the car floor and tends to seep under the interior walls of the car and to cause disintegration of 15 inaccessible woodwork and the heat insulating material which is frequently placed between the inner and outer walls of refrigerator cars.

My invention contemplates the provision 20 of a seal which will adapt itself to irregularities in the contiguous portions of a floor and a wall and produce a water-tight joint between them, which easily may be applied and which is relatively inexpensive.

25 In the accompanying drawings illustrating a preferred embodiment of my invention:

Figure 1 is a fragmentary section of a railway refrigerator car having a joint sealed in accordance with my invention;

30 Figure 2 is a perspective view of the preferred form of rubber sealing strip which I employ in forming my improved seal;

Figure 3 is a top plan view of the strip;

35 Figure 4 is a sectional view of the contiguous portions of the floor and wall and the elements of the seal as they appear prior to the completion of the joint, and

Figure 5 is a similar view illustrating the completed joint.

40 Similar characters of reference refer to similar parts throughout the several views.

In Figure 1 reference numeral 6 indicates the floor, and the numerals 7, 8 and 9 the inner, intermediate and outer walls of a refrigerator car of conventional construction. The spaces between the walls may be dead air spaces or may be filled, or partially filled, with heat insulating material indicated at 10.

50 The inner wall 7 is preferably formed of horizontally disposed lumber provided with the usual cooperating tongues and grooves. It is perhaps not essential that all of the boards of the wall 7 be provided with tongues and grooves, but it is desirable that 55 the lowermost board of this wall be provided

with a longitudinal groove 11 in the edge thereof which is presented to the floor.

The sealing strip is formed of a compressible resilient material such as relatively soft rubber, and comprises a longitudinal web 12 60 formed integral with flanges 13—13 which, when the strip is not under compression, diverge downwardly from the web 12 and provide between them a groove of inverted V-shape. The tongue 12 is adapted tightly to 65 fit within the groove 11 of the lowermost board of wall 7, and, if desired, may be slightly tapered upwardly in its vertical section, the upper edge of the web being somewhat narrower than the groove 11, and the 70 lower portion of the web being slightly greater than the width of the groove 11.

75 The flanges 13 are preferably of such width that when they are compressed as illustrated in Figure 5, their free longitudinal edges lie substantially flush with the sides of the wall board which they underlie. I prefer to provide each flange 13 with a plurality of apertures 15 disposed in parallel rows, the apertures of one row 80 being staggered with respect to those of the other row.

In making the preferred seal embodying 85 my invention, the web 12 of the rubber sealing strip is fitted into the groove 11 of the lowermost wall board, and the latter is brought down to the position shown in Figure 4 with an initially plastic sealing compound 16 (preferably including asphalt as one of its constituents) in the space between 90 the floor and the walls of the groove 14. The plastic sealing joint either may be placed upon the floor along a line directly under the position to be occupied by the lowermost wall board, or may be placed in the groove 95 14 before the said wall board and the sealing strip are brought to the position shown in Figure 4.

With the several elements occupying the 100 position shown in Figure 3, and with the 105 compounds 16 still plastic, the lowermost wall board is forced down toward the floor substantially to flatten out the sealing strip flanges 13 under the margins of the groove 11, as illustrated in Figure 4. When this operation has been accomplished, the plastic sealing material flows upwardly through the apertures 15 to overlie, as well as to underlie, the flanges of the sealing strip. The said 110 wall board is then nailed or otherwise se-

cured in position, and the composition 16 hardens, or partially hardens, as the case may be.

I contemplate that in some cases I may dispense with the sealing composition 16 and that the cross section of the sealing strip may be varied. Thus I do not limit myself to the specific construction and arrangement of parts herein claimed and described.

What I claim is new and desire to secure by Letters Patent, is:

1. The combination of a floor and a wall board to be fitted thereto, said wall board having a longitudinal groove in the edge thereof adjacent said floor, with a deformable sealing strip having a web adapted to be received in said groove and flanges diverging from said web forming a groove in the bottom of said strip, and unstable plastic sealing compound in said latter groove, whereby said sealing compound is distributed between said floor and strip when said wall board is pressed against said floor.

2. The combination of a floor and a wall board to be fitted thereto, said wall board having a longitudinal groove in the edge thereof adjacent said floor, with a resilient rubber sealing strip having a web adapted to be received in said groove and flanges diverging from said web forming a groove in the bottom of said strip, and initially plastic sealing compound, including asphalt as a constituent in said latter groove, whereby said sealing compound is distributed between said floor and strip when said wall board is pressed against said floor.

3. The combination of a floor and a wall board to be fitted thereto, said wall board having a longitudinal groove in the edge thereof adjacent said floor, with a deformable sealing strip having a web adapted to be received in said groove and flanges diverging from said web forming a groove in the bottom of said strip, said flanges having a plurality of openings therethrough, and unstable plastic sealing compound in said latter groove, whereby said sealing compound is distributed between said floor and strip and passing through said openings is

also distributed between said flanges and wall board when said wall board is pressed against said floor.

4. The combination of a floor and a wall board to be fitted thereto, said wall board having a longitudinal groove in the edge thereof adjacent said floor, with a resilient rubber sealing strip having a web adapted to be received in said groove and flanges diverging from said web forming a groove in the bottom of said strip, said flanges having a plurality of openings therethrough, and initially plastic sealing compound, including asphalt as a constituent, in said latter groove, whereby said sealing compound is distributed between said floor and strip and passing through said openings is also distributed between said flanges and wall board when said wall board is pressed against said floor.

5. The combination of a floor and a wall board to be fitted thereto, said wall board having a longitudinal groove in the edge thereof adjacent said floor, with a deformable sealing strip having a web adapted to be received in said groove, a lateral flange on said web and a groove in the bottom of said strip, and unstable plastic sealing compound in said latter groove, whereby said sealing compound is distributed between said floor and strip when said wall board is pressed against said floor.

6. The combination of a floor and a wall board to be fitted thereto, said wall board having a longitudinal groove in the edge thereof adjacent said floor, with a resilient rubber sealing strip having a web adapted to be received in said groove, a lateral flange on said web and a groove in the bottom of said strip, and initially plastic sealing compound, including asphalt as a constituent, in said latter groove, whereby said sealing compound is distributed between said floor and strip when said wall board is pressed against said floor.

In witness whereof, I hereunto subscribe my name this 9th day of September, 1924.

WILLIAM R. GILLIES.
